CLAIM

The ornamental design for a towel warming device, as shown and described.

DESCRIPTION

FIG. 1 is a perspective view of a towel warming device showing my new design;

FIG. 2 is a front elevation view of a towel warming device showing my new design;

FIG. 3 is a top plan view of a towel warming device showing my new design;

FIG. 4 is a side elevation view of the towel warming device showing my new design; and,

FIG. 5 is a back elevation view of the towel warming device showing my new design.

In the drawings, the broken lines depict environmental subject matter only and form no part of the claimed design.
